UNITED STATES PATENT OFFICE.

KUSTA ROPERT KOSKINEN, OF BROOKLYN, NEW YORK.

FREIGHT-CAR DOOR.

Application filed January 5, 1923. Serial No. 610,863.

To all whom it may concern:

Be it known that I, KUSTA ROPERT KOSKINEN, a citizen of Finland, and a resident of the city of New York, borough of Brooklyn, in the county of Kings and State of New York, have invented a new and Improved Freight-Car Door, of which the following is a full, clear, and exact description.

10 This invention relates to freight-car doors, and more particularly aims to provide a new and improved door and doorway construction particularly adapted for use in loading and unloading grain or the like or any commodity in loose bulk and composed of a number of small and generally perishable elements which must be carefully and completely housed during transport and the handling of which has heretofore presented 20 serious difficulties of loading and unloading due to the instability and excessive weight of the mass.

It will thus be understood that the invention is particularly valuable in connection with the shipping of grain, as the perishability, instability and weight of a mass of such commodity renders the same one of the most troublesome and difficult kind of freight to handle.

30 According to the present invention, a solution for this very aggravating problem is offered in the way of a construction including essentially a sliding door (preferably involving the combination of a main door structure to be removed for unloading and a minor door forming a part of the main door structure and used for loading with the main door locked securely in closed position), a recessed doorway for receiving the main door, and a novel suspension for such door to permit the latter to be made of massive size and construction and yet easily swung into or out of its doorway and moved toward or away from the doorway in a substantially vertical plane; the new combination also having preferably associated therewith simple yet reliable means for clamping and locking the door closed, and additional means for holding the door temporarily, and during sliding of the same in a substantially vertical plane away from the doorway, against certain of the possible adjustments and movements of the door.

55 The invention will be more clearly understood from the following description, when taken in connection with the accompanying

drawing showing as one example of the invention a preferred embodiment thereof.

In this drawing:

Fig. 1 is a side elevation of a part of a 60 freight-car, with the new main door closed;

Fig. 2 is a view similar to Fig. 1, but showing such door opened and slid beyond its doorway;

Fig. 3 is a vertical section on an enlarged 65 scale taken through door and doorway at about the line 3—3 in Fig. 1;

Fig. 4 is a view similar to Fig. 3 but with the main door in a position intermediate that shown in Figs. 1 and 2; 70

Fig. 5 is a fragmentary view, being a horizontal section taken on line 5—5 of Fig. 3;

Fig. 6 is an enlarged detail view, showing in top plan an end portion of the door-suspending sliding carriage. 75

Similar reference characters refer to similar parts throughout the several views of the drawings.

Referring to Figs. 1 and 2, the wall 6 80 may be the side wall of a freight-car which somewhere along its length is provided with a recessed doorway as indicated at 7 in Fig. 2, so as to present the equivalents of jambs and a still on which may be 85 hingedly mounted as indicated a pair of outwardly opening strips 8 and a third outwardly opening strip 9. The main door is indicated at 10 and when disposed as shown in Figs. 1 and 3, so that its rear face abuts 90 against the frame structure 11, the two side clamping strips 8 may be swung in from the positions shown in Figs. 2 and 4 to the positions shown in Figs. 1 and 3, to temporarily clamp the main door in place, and thereupon the hinged strip 9 at the sill 95 of the doorway may be swung in against the outer lowermost portion of the door, thus further to clamp the door tightly and rigidly in place and to lock the hinged strips 8 in their own clamping positions. To facilitate quick opening and closing of these hinged strips, the side strips 8 carry 100 suitable handles 8^a and the bottom strip 9 carries a suitable handle 9^a which is desirably hingedly mounted as indicated.

The novel suspension means for the door forming one of the very important features of the present invention includes here an elevated track 12, and a rockable and slideable carriage on the track. Such carriage includes a pair of rollers 13 mounted as 110

hereinafter described. In order to permit the rocking movement just described as well as a sliding movement of said carriage, rollers 13 are crowned as indicated in Figs. 3 and 4 and track 12 is of circular cross-section as illustrated.

Said suspension means further includes a pair of depending arms 16, of inverted L-shape as shown in Figs. 3 and 4, and carrying at their lower ends eyes 17 loosely engaging perpendicularly arranged eyes 18 carried rigidly by the exterior of the door at points well below the top of the door; and not only are the inner ends of the upper horizontal lengths of the arms swiveled in the end portions of the carriage 15—as shown best in Fig. 6, and as will be described in a moment,—to permit said arms to swing from side to side as viewed in Fig. 1, but such end portions of the carriage are slightly relatively movable because each is a separate tubular member as illustrated in Fig. 1 and both are interconnected solely by means of a bar 19 which they house and which bar is joined at opposite ends to the carriage portions by cross pins 20 riveted to the carriage portions but passing loosely through holes in the bar. As just mentioned, the upper horizontal length of each arm 16 is swivel-mounted at its inner end on carriage 15; this mounting being, as shown in Fig. 6, as follows: The inner end of such length of the arm is reduced as at 16^a and received loosely in the journal-bore cut axially of the transverse terminal sleeve 15^a at its end of the carriage. Roller 13, a collar 14, and a washer 14^a, are all secured in place as shown, by a stud 13^a threaded at its inner end into the inner end of reduced portion 16^a of arm 16.

The suspension means just described permits the door 10, despite its great weight and bulk (as is necessary for strength), and the design of such door and the doorway 7, whereby the door must be tightly and snugly fitted in the latter to advance to closing position (as is also necessary, especially where grain is to be transported by the car), to be easily swung out of the doorway, by means of a handle 10^a near the bottom exterior of the door, once the hinged strips 8 and 9 are swung to the positions shown in Fig. 4; such easy handling of the massive door 10 being incident to the lost motions permitted in the carriage 15 and at the eye connections 17—18, as well as the universal joints substantially provided at the latter points and the swiveled upper ends of arms 16, and, finally, the rockable as well as slidable mounting of the carriage itself due to the crowned rollers 13.

In order to provide means for temporarily holding the door 10 to substantially vertical suspension from the carriage 15, as is desirable once the door is sufficiently clear from doorway 7, so that thereupon the door may be

easily pushed to the left of Fig. 1 and so moved with the carriage to the position shown in Fig. 2, the following parts, in addition to the handle 10^a, are provided. A pendant chain loop 21 has its opposite ends anchored as at 22 (Fig. 3) to the upper exterior of the door near the opposite sides thereof; and below such points of anchorage the chain passes over rollers 23 revolvably mounted on the arms 16 and also under rollers 24 revolvably mounted on the door exterior.

Thus, once the door 10 is sufficiently clear from doorway 7, that is, when the upper part of the door is sufficiently clear of the doorway, a single down-pull on the lower-most intermediate portion of chain 21 instantly throws the door and the carrying and hanger parts to the relative positions shown in Fig. 4, whereupon the chain is arranged under the handle 10^a as shown in Fig. 2, and the door is securely held against movement of any kind relative to arms 16 or to the carriage 15; and so door and carriage may be slid easily back and forth toward and away from the doorway. According to the construction shown, it will be noted that the door 10 will not be suspended strictly in a vertical plane as illustrated in Fig. 4, when the parts are arranged as shown in Fig. 4, as the lower end of the door will have a tendency to swing in under the elevated track 14. It is not deemed necessary here to suggest any particular means for holding door 10 exactly in such a vertical plane; as it has been found a very simple and comparatively effortless matter to hold the door thus vertical while transferring the same from the position of Fig. 1 to that of Fig. 2 and vice versa.

The parts are disposed as in Fig. 2 for unloading the contents of the freight car; and when the car is emptied, door and carriage are slid back to dispose the door in front of doorway 7, and then chain 21 is disengaged from handle 10^a, the door is manipulated relative to its various relatively movable suspension or hanger elements while being pushed into place deep in the recessed doorway at the bottom thereof, then is wholly pushed back into the doorway against frame structure 11, and finally the hinged strips 8 and 9 are closed in, in the order named, to clamp the door and the strips 8 into place.

It will be noted that an important feature of the invention is that the sliding and suspension means are always permanently connected to the door 10.

When, however, a freight car is to be loaded, the door 10 may be left in closed and clamped position, as means are provided for permitting loading under such circumstances, and most efficient and rapid loading. In this connection door 10 is provided with a hingedly hung section 25 which may be

swung up and away from the main portion of the door to establish an opening corresponding in outline to said section near the top of door 10 and the freight car, and 5 through which opening the grain or the like may be shovelled or shot into the car until the latter has received its predetermined load. When the car is so loaded, the section 25 is of course lowered to complete 10 the closure of the doorway by door 10.

Locking means between door 10 and bottom clamping strip 9, and between section 25 and the adjacent part of the door, are not shown; it of course being understood 15 in this connection that any suitable locks may be employed as desired, at those points or elsewhere, and whether or not car-seals of the familiar type are employed.

Inasmuch as many changes could be made 20 in the above construction, and many apparently widely different embodiments of my invention could be made without departing from the scope thereof, it is intended that all matter contained in the above description 25 or shown in the accompanying drawings shall be interpreted as illustrative and not in a limiting sense.

It will also be understood that the language used in the following claims is intended 30 to cover all the generic and specific features of the invention herein described and all statements of the invention which, as a matter of language, might be said to fall therebetween.

35 I claim:

1. In a freight car door structure including a recessed doorway in a vertical wall of the car, an overhead horizontal track longer than the width of the doorway, a carriage 40 slideable along and rockable laterally of the track, a plurality of hanger elements vertically suspended from the carriage for

swinging movements in a plane parallel to the plane of the doorway, a door pivotally suspended from the lower ends of said hanger elements thereby to permit, relative to the car, translational movements of the door in a given plane, swinging movements of the door toward and away from said plane, and rotational movements of the door in said plane, and means for giving the door any or all of such movements at will, said means including a flexible element having a central pendant loop portion movably suspended outside the door and having the terminal portions of the element operatively associated with the hangers and also with the door.

2. In a freight car door structure including a recessed doorway in a vertical wall of the car, an overhead horizontal track longer than the width of the doorway, a carriage slideable along and rockable laterally of the track, a plurality of hanger elements vertically suspended from the carriage for swinging movements in a plane parallel to the plane of the doorway, a door pivotally suspended from the lower ends of said hanger elements thereby to permit, relative to the car, translational movements of the door in a given plane, swinging movements of the door toward and away from said plane, and rotational movements of the door in said plane, and means for giving the door any or all of such movements at will, said means including a flexible element having a central pendant loop portion movably suspended outside the door and having the terminal portions of the element operatively associated with the hangers and also with the door at a plurality of vertically spaced points.

KUSTA ROPERT KOSKINEN.
